United States Patent Office

Des. 190,928
Patented July 18, 1961

190,928

COMBINATION SCALE AND VALET STAND

Henry de S. Lauve, Grosse Pointe, Mich., assignor to Fairbanks, Morse & Co., Chicago, Ill., a corporation of Illinois

Filed Dec. 16, 1960, Ser. No. 63,328

Term of patent 14 years

(Cl. D52—10)

FIG. 1

FIG. 1 is a front view of a combination scale and valet stand showing my new design;

FIG. 2 is a side view of the scale of FIG. 1;

FIG. 3 is an enlarged front perspective view of the upper portions of the scale of FIG. 1; and

FIG. 4 is a rear view of the upper portions of the scale of FIG. 1.

The undisclosed side of the scale is substantially the same in appearance as the side shown.

I claim:

The ornamental design for a combination scale and valet stand, as shown and described.
